UNITED STATES PATENT OFFICE.

JOHN O. WOODSOME, OF NEW YORK, N. Y.

VALVE-CONTROLLING APPARATUS.

Application filed June 16, 1926. Serial No. 116,306.

This invention relates to valve controlling apparatus for steam drying system such as paper machine driers and the like.

For the economical operation of steam drying systems, it is important where possible to use low pressure steam and to maintain as low a back pressure on the system as is consistent with obtaining the desired temperature in the driers and with obtaining an efficient transfer of heat from the steam to the drying cylinders. In order to utilize the sometimes limited and varying available supplies of the exhaust steam from primary movers, such as steam engines, pumps and turbines, in the drying system, various types of control apparatus have been devised for supplementing such low pressure steam with live steam. The economy of the system depends upon the efficiency of such control apparatus.

It is, therefore, an object of this invention to provide a valve controlling apparatus for drying systems, using both low and high pressure steam that will automatically regulate the flow of live steam to the driers, whereby a uniform pressure may be maintained in the driers without the use of unnecessary quantities of live steam.

It is a further object of this invention to provide a steam drying system wherein automatically operated diaphragm controlled valves are utilized for controlling the flow of low pressure and high pressure steam to the driers in accordance with the pressure requirements of said driers to maintain the highest drying efficiencies consistent with economical use of the steam.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary elevational view of my valve controlling apparatus as applied to a drying system for paper machines, with parts of the valves broken away and in section to show their construction.

Figure 2 is an enlarged sectional view of one of the valves.

Figure 3 is a broken view of a modified form of valve control for a drying system.

As shown on the drawings:

The reference numeral 1 indicates a steam

drier header or manifold leading to a steam using apparatus such as the drying cylinders of a paper machine. A diaphragm controlled valve 2 (Figs. 1 and 2) is adapted to be connected in at the intake end of said header 1 to control the flow of steam into the header. The particular structure of said valve 2 will appear hereinafter. A low pressure steam supply pipe 3 is connected to the other side of said valve 2 by means of flanged piping 4, bolted together in the usual way. At some point such as 5, a live steam line 6 is connected into said piping 4, a diaphragm valve 7 being placed in said live steam line 6 for controlling the flow of live steam into the piping 4.

The valves 2 and 7 will now be described. Valve 2 (Fig. 2) comprises a globular body portion 8 having flanged ends 9 and an inner double-ported valve seat wall 10. Said valve wall 10 is integrally formed with the body portion 8 and is provided with aligned upper and lower ports 11 having beveled valve seats 12. The top face of said body portion 8 is flattened, as at 13, and a valve operating device 14 is bolted or otherwise secured thereto. Said device 14 comprises upper and lower stuffing boxes 15 and 16, spaced apart by arms 17. A valve stem 18 is adapted to pass through said stuffing boxes 15 and 16 and through packing glands 19 and 20 threaded therein. Said valve stem 18 carries a pair of spaced valves 21 adapted to seat in the valve seats 12. The upper stuffing box 15 is provided with a recessed and flanged upper face 22, adapted to form with a similarly flanged and recessed cap 23 a chamber 24. A flexible diaphragm or disc 25 secured to the upper end of said valve stem 18 is adapted to be clampingly held at its periphery between said flanged face 22 and the flanged cap 23. Threaded passages 26 and 27 are provided in the face 22 and the cap 23, respectively, communicating with the chamber 24 on opposite sides of the diaphragm 25. Piping 28 and 29 connect with said passages 26 and 27 respectively, the piping 28 leading to a pipe 30 for conducting some fluid such as air under measured pressure, and the piping 29 connecting with the drier header 1. A lever arm 31 is pivoted at one end to an arm 17 and is secured intermediate its ends to the valve stem 18. The free end of said lever 31 carries a slidably mounted weight 32, for adjusting the pressure of the valves 21 against their valve seats 12.

Valve 7 is similar in construction to valve 2, but since its valves 33 are intended to be closed the greater part of the time, the weighted lever arm 34 is pivoted at one end to the valve stem 35 and intermediate its ends to an arm 36. Piping 38 and 37 lead from the upper and lower halves of the diaphragm chamber 39 to the low pressure steam line 3 and to the pipe 30, respectively. Said pipe 30 is provided with a pressure gauge 40 and a valve 41 for regulating the pressure of the air or other fluid to the pressure desired to be maintained in the dryer header.

The operation of the valve controlling apparatus is substantially as follows: Whenever the pressure in the drier header falls below that desired as shown on the gauge 40, the differential pressure in the diaphragm chamber 24 of valve 2 causes the diaphragm 25 to flex upwardly, thereby raising the valve stem 18 and opening the ports 11. The low pressure steam from the supply line 3 thereupon is admitted to the drier header. If, however, the pressure of said low pressure steam is not sufficient to bring the pressure in the drier header 1 up to that recorded by the gauge 40, the differential pressure in the diaphragm chamber 39, brought about by the pressures in the respective lines 37 and 38, will cause the valve stem 35 to move upwardly to open the valves 33 and admit high pressure steam from the line 6 into the drier header. In this way, the pressure in the drier header is rapidly and automatically brought up to the desired pressure. As soon as the pressure recorded on the gauge 40 is exceeded by the pressure in the drier, the diaphragm 25 of valve 2 operates to close the valves 21 entirely. Similarly, when the pressure in the low pressure steam line 3 exceeds that of the pressure gauge 40, the diaphragm of valve 7 operates to close the valves 33 to shut off the live steam.

It will be evident, therefore, that when the desired pressure in the drier header can be maintained by the use of low pressure steam alone, no live steam will be admitted, but that when the pressure in the drier header falls below the required amount the low pressure steam will be supplemented by live steam in just sufficient quantity to maintain the desired pressure in the drier header. The resulting saving from such automatic control of the steam is apparent.

In Fig. 3 there is shown a slightly modified layout in which the reference numeral 42 indicates a drier header. An exhaust steam line 43 is connected through piping 44 directly to said drier header 42 without any intermediate valves, and a live steam line 45 is connected to said header 42 through a diaphragm-controlled valve 46. A similar valve 47 in the line 44 connects the exhaust steam line 43 with an exhaust relief line 48.

Said valves 46 and 47 are operated as above described by means of diaphragm-mechanisms 49 and 50 respectively, each connected to a source of air or other fluid made pressure and to the drier header. A pipe 51 admits the air or other fluid under pressure through a regulating valve 52 into piping 53, provided with a gauge 54. The pressure in the line 53 is transmitted through the pipes 55 and 56 respectively to the lower side of the valve diaphragms 49 and 50. The upper sides of said diaphragms 49 and 50 are connected by pipes 57 and 58 to the drier header 42.

If, now, the pressure in the drier header 42 falls below the desired pressure as recorded on the gauge 54, the diaphragm 49 operates to open the valve 46 to admit live steam. Otherwise, the exhaust steam only is used. When the pressure of the exhaust steam is greater than that desired in the drier header, the valve 47 is opened by automatic operation of the diaphragm-mechanism 50 to vent the excess exhaust steam.

The results attained in both the arrangements of valve controlling apparatus are substantially the same, in that only low pressure steam is used when possible to maintain the desired pressure. In the modified arrangement, further provision is made to cut down the back pressure in the exhaust steam line by inserting an automatically operated exhaust relief valve. Otherwise the back pressure in the exhaust steam line might build up sufficiently to seriously lower the efficiencies of the engines or other primary movers from which the exhaust steam is being obtained.

I am aware that numerous details of construction may be varied through a wide range without departing from the principles of this invention, and I therefore, do not purpose limiting the patent granted otherwise than necessitated by the prior art.

I claim as my invention:

In a steam drying system including a drying header, a low pressure steam line, a valve between said low pressure steam line and said header, valve closing means on said valve responsive to the steam pressure of said header, a high pressure steam line, a valve between said high pressure steam line and said low pressure steam line, valve closing means on said last named valve responsive to the steam pressure of said low pressure steam line, and means for simultaneously varying the responsivity of said valves to their respective steam pressures, said means comprising a source of air under regulatable pressure, and means for admitting the air from said source of pressure for opening the valves.

In testimony whereof I have hereunto subscribed my name.

JOHN O. WOODSOME.
